UNITED STATES PATENT OFFICE

2,516,190

APPARATUS FOR CHARGING BLAST FURNACES

Robert S. A. Dougherty and John E. Eberhardt,
Bethlehem, Pa., assignors to Bethlehem Steel
Company, a corporation of Pennsylvania

Application April 7, 1945, Serial No. 587,106

9 Claims. (Cl. 214—36)

1

This invention relates in general to an apparatus and method for the operation of blast furnaces, and more particularly to an apparatus and method for preventing the erosive wear of blast furnace parts incident to the leakage of dust-laden gases.

It has been discovered that by working blast furnaces at higher top pressures than normal there accrue benefits in smoothness of operation, decreased dust losses, increased tonnage, and decreased coke/ore ratio.

Bell-and-hopper structures, however, cannot be made perfectly gastight, even for ordinary pressures, and at high pressures the strong erosive action of the dust-laden gases escaping through the numerous unavoidable leaks very quickly causes excessive wear. It should be noted, however, that the rate of wear is increased only at the places where the leakage occurs. Within the furnace, offtakes, etc., the erosive effect of the dirty gases is less, because of their lower velocity.

One object of this invention, therefore, is to provide means for permitting efficient and economical use of high top pressures in blast furnaces.

Another object is to provide means for preventing excessive wear of blast furnace bells and hoppers due to leakage of erosive dust-containing gases.

Other objects and purposes of the invention will appear hereinafter in the specification and in the appended claims.

Referring now to the attached sheet of drawing, the single diagrammatic figure thereon illustrates a blast furnace top 1, provided with the offtake 2, and three superposed charge-receiving hopper chambers comprising the upper hopper chamber 3, the intermediate hopper chamber 4, and the lower hopper chamber 5, through which hopper chambers the materials may drop successively to the furnace stack 6. Each hopper chamber is provided as shown with a bell, comprising the small bell 7 closing the bottom of hopper chamber 3, the intermediate bell 8 closing the bottom of hopper chamber 4, and the large bell 9 closing the bottom of hopper chamber 5. Manipulating means for lowering and raising the bells comprise the rod 10, attached to the bell 9, and the concentric sleeves 11 and 12 attached to the bells 8 and 7 respectively.

The lower hopper chamber 5 is provided with the pipe 13 for admitting clean outside gases to said hopper chamber. The pipe 14 provided with equalizing valve 15 connects the hopper chambers 4 and 5, and the relief valve 16 and pipe 17 vent the intermediate hopper chamber 4 to the atmosphere.

In practice, the gas pressure in the furnace stack 6 is controlled at the point of most efficient operation for the particular blast furnace, but the pressure in the lower hopper chamber 5 is

2

kept slightly in excess of that in the furnace stack 6 by admitting clean gas, e. g., cleaned blast furnace gas, at a properly regulated pressure through the pipe 13.

With the equalizing valve 15 closed and the relief valve 16 open a charge is placed by the conventional skip hoist in the upper hopper chamber 3. The pressure in the intermediate hopper chamber 4 will be substantially that of the atmosphere permitting the small bell 7 to be lowered and thereby dropping the materials of the charge into said hopper chamber 4. Said small bell 7 being raised again into position, the relief valve 16 is closed and the equalizing valve 15 is opened. Gas then flows through pipe 14 until the pressure in hopper chamber 4 equals that in hopper chamber 5, permitting the intermediate bell 8 to be lowered and thereby dropping the materials of the charge into said hopper chamber 5. Equalizing valve 15 is then closed and relief valve 16 opened and the above described cycle is repeated until the proper number of charges has been placed in hopper chamber 5. Since the pressure in hopper chamber 5 is maintained at all times slightly in excess of that in the furnace stack 6, the large bell 9 may be lowered at the proper time thereby dropping the materials being charged into said furnace stack 6.

The small leakage of clean gas from the hopper chambers 4 and 5 will have no erosive effect on the bell seats or other parts, and likewise there will be no trouble from clogging or wear due to dust in the pipe 14 or equalizing valve 15. It is necessary to clean the blast furnace gas in any event, for use in blowing engines, stoves, boilers, etc., so the return of a small portion in this manner will impose only the slight additional expense of compressing it to the desired pressure.

Although we have hereinabove described our invention in considerable detail, we do not wish to be limited narrowly to the exact and specific particulars disclosed, but may use such substitutes, modifications, or equivalents as are included within the scope and spirit of the invention or pointed out in the appended claims.

In accordance with the statute, we desire to claim:

1. In the charging mechanism for operating a blast furnace comprising three superposed hopper chambers above the stack, means for introducing clean gas at a higher than stack pressure into the bottom hopper chamber, and means for transferring said gas from said bottom chamber into the next above hopper chamber when required to equalize pressures therebetween.

2. In the charging mechanism on the top of a blast furnace above the stack, the combination of a plurality of hopper chambers, each having a bottom bell, superposed above said stack, and means for maintaining a higher than stack pres-

sure of clean gases in one or more of said hopper chambers.

3. In the charging mechanism on the top of a blast furnace above the stack chamber, the combination of a hopper chamber having a bottom bell opening into the stack chamber, a pipe line for admitting clean gas at a pressure in excess of that of the gases in the stack chamber into said hopper chamber, a second hopper chamber having a bell opening into the first hopper chamber, a second pipe line having a valve for equalizing gas pressures between the first and second hopper chambers, a relief valve on the second hopper chamber for bleeding surplus gas therefrom, and a third hopper chamber having a bell opening into the second hopper chamber.

4. In a blast-furnace charging-system having an upper receiving-hopper internally at atmospheric-pressure, its cooperating bell, actuating-means opening and closing said bell intermittently, a lower delivery-hopper and its bell discharging into the top of the furnace, operating-means opening and closing said delivery-hopper bell intermittently, a conduit connecting said hoppers together, and means to feed charging material into said receiving-hopper intermittently, the novel improvement of the combination of means including a valve-construction in said conduit dividing said conduit into an upper chamber and a lower chamber, the latter including said delivery-hopper, means to open and close said valve-construction intermittently, means to feed substantially-nonabradant inert gas under pressure into said lower chamber and maintain the gas-pressure in said lower chamber at all times greater than the gas-pressure in the top portion of the furnace, means to feed substantially-nonabradant inert gas under said specified pressure into said upper chamber, means controlling said gas fed into said upper chamber to maintain equalized gas-pressure on opposite sides of said valve prior to and during the open condition of the latter, means connecting said upper chamber to the external-atmosphere, and means controlling the passage of gas from said first chamber to the atmosphere to provide atmospheric-pressure in said upper chamber on the underside of said receiving-hopper bell prior to and during the open condition of said bell.

5. The novel combination in a blast-furnace charging-system set forth in claim 4, in which said valve-construction includes an intermediate-hopper and its bell discontinuously receiving the charging material discharged from said receiving-hopper and interruptedly dumping it into said delivery-hopper.

6. In the charging-system of a blast-furnace operating under a high gas-pressure in its top portion, said charging-system having an upper receiving-hopper internally at approximately atmospheric-pressure and its bell, actuating-means intermittently opening and closing said bell, a lower delivery-hopper and its bell discharging into the top portion of the furnace, a conduit connecting said hoppers together, and means to feed charging material intermittently into said receiving hopper, the novel improvement of the combination of an intermediate-hopper and its bell in said conduit between said hopper and dividing said conduit into an upper chamber and a lower chamber, the latter including said delivery hopper, said intermediate-hopper and its bell acquiring its material from

said receiving-hopper and discharging it into said delivery-hopper, means to intermittently open and close said intermediate-hopper bell, means to deliver substantially-nonabradant inert gas at higher pressure than that in the top portion of the furnace into said lower chamber and maintain said higher gas-pressure therein during the operation of the furnace, means to feed substantially-nonabradant inert gas under said higher pressure into said first chamber, means to control the feed of said gas into said first chamber to equalize the pressures on the opposite sides of said intermediate-hopper bell prior to its opening and while it remains open, means connecting said upper chamber to the external-atmosphere, and means controlling the passage of gas therethrough to the atmosphere to provide substantially-atmospheric gas-pressure in said first chamber prior to the opening of said receiving-hopper bell and while the latter is open.

7. In a blast-furnace charging-system of known type having an upper receiving-hopper and its bell, actuating-means opening and closing said bell intermittently, a lower delivery-hopper and its bell discharging into the top of the furnace, and operating-means opening and closing said delivery-hopper bell intermittently, the novel improvement of means for continuously maintaining the interior of said delivery-hopper with substantially-nonabradant inert gas at a super-atmospheric pressure greater than that in the top of the furnace during the operation of the latter.

8. In a blast-furnace charging-system of known type having an upper receiving-hopper and its bell, actuating-means opening and closing said bell intermittently, a lower delivery-hopper and its bell discharging into the top of the furnace, and operating-means opening and closing said delivery-hopper bell intermittently, the novel improvement of means for continuously maintaining the interior of said delivery-hopper with substantially-nonabradant inert gas at a super-atmospheric pressure at all times greater than the gas-pressure in the top portion of the furnace during operation of the latter.

9. In a blast-furnace charging-system of known type having an upper receiving-hopper and its bell, actuating-means opening and closing said bell intermittently, a lower delivery-hopper and its bell discharging into the top of the furnace, and operating-means opening and closing said delivery-hopper bell intermittently, the novel improvement of means to maintain at all times a pressure in said delivery-hopper with substantially-nonabradant inert gas at a pressure greater than the super-atmospheric pressure in the top portion of the furnace during the operation of the latter.
